ORE CONCENTRATION

Harry H. Burton, Whitman, Mass., assignor to
 Burton-Allen Gold Reclaiming Corporation,
 Wilmington, Del., a corporation of Delaware

Application September 10, 1936, Serial No. 100,140

2 Claims. (Cl. 209—455)

The present invention relates to an improved means and method for concentrating the "values" contained in ores, sands, and like materials—the object being to subject such materials, 5 in the form of free-flowing pulps, to repeated progressive removals therefrom of the "gangue" or lighter worthless matter—thereby to obtain, efficiently and economically as the process continues, a richer and richer concentrate of the 10 heavier "values" or metalliferous substances.

My invention provides a compact apparatus into and through which the metal-bearing material in wet pulp form flows at a regulable rate, and from which there are a plurality of slime 15 discharges carrying off the "gangue" or waste at nearly the same rate—the small difference being represented, for all practical purposes, by a single constant delivery of a concentrated pulp residue which is exceedingly rich in values.

20 My invention is applicable to the treatment of practically all varieties and grades of crushed or divided ores and metal-bearing sands, or similar materials containing "values", which are susceptible of forming with water, or other liquid, 25 a free-flowing pulp—it being immaterial what previous treatment such materials have been subjected to, or whether or not any free gold, silver, or other "values" contained therein have previously been removed. It is well known that in 30 many ores, metal-bearing sands and like materials, no matter how finely crushed or divided, the "values" do not exist in a free or relatively pure state, but instead are combined more or less intimately with other substances; for example, much of the gold in such crushed ores, 35 sands and like materials is so combined or coated with sulphides that it cannot possibly be isolated from the lighter particles or "gangue", either by the mercury amalgamation process, or by the 40 cyanide process—in both of which there is inevitably a heavy loss of such "values". My invention 45 lends itself to the concentration and recovery, economically and efficiently, of all such "values" as are difficult, if not impossible, to recover by the various methods of concentration heretofore practiced.

By my invention, as hereinafter described, the separation and discard of the worthless and lighter substances in the pulp is effected continuously and progressively during the passage of the pulp through my improved apparatus, wherein said pulp, as fast as received, is subjected to an initial expulsion therefrom of slimes that contain and carry off a considerable portion of 55 the "gangue" or lighter worthless ingredients—

thus progressively creating at a much-reduced volumetric rate an intermediate product in the form of a pulp residue which is relatively rich in the heavier "values" or metalliferous ingredients. On such residue, as fast as formed, is 5 repeated the above-described slime-expelling operation—this, of course, still further materially decreasing the volume of and increasing the value-concentration in the pulp residue that, as a second intermediate product, is progressively 10 obtained by the above described action. In this way, by repeating for as many times as is necessary the slime-expelling operation, each time on a smaller-volume more concentrated pulp residue, there is obtained at the end of the process 15 a single constant small discharge of an exceedingly rich concentrate of all the heavier "values" or metalliferous substances contained in said pulp. Other and further objects and advantages of the invention will be made apparent in the following detailed description thereof, 20 reference being had in this connection to the accompanying drawing, wherein the single figure is a sectional view illustrating the principles of my invention, and showing one form and arrangement of apparatus for carrying it into effect.

Referring to said drawing, I have shown a plurality of concentrating traps arranged in series, and it will be obvious that any desired 30 number of such traps similarly arranged may be employed, depending upon the character of the pulp and the degree of concentration required. Said traps, except for size, are substantially identical in construction, each comprising 35 in the illustrative form shown, a base portion 1, upon which is suitably mounted a shell 2, the latter providing a chamber 3 into which the pulp is fed by a suitable duct or tube 4, the latter passing through the inclosed top 5 of chamber 3 and having its outlet near the bottom of said 40 chamber. Said bottom is constituted by a rack or plate 6 having relatively large openings over its entire area, these openings permitting the free passage therethrough of any and all of the 45 particles or solid matter carried in suspension by the pulp; however, the openings in plate or rack 6 do not permit the passage therethrough of any of the relatively large "rags" 7, 7 which, as shown in the drawing, occupy much of the 50 space in chamber 3—the rack or plate 6 serving as a support for this mass of "rags". The latter are preferably of clay in substantially spherical form, and they preferably surround the entrance tube 4 to about the level of a lateral 55

opening 8 in the upper part of shell 2, and at or near such level is provided a substantially horizontal shelf 9, for a purpose to be hereinafter described.

5 Below the opening 8, the shell 2 has another opening 10, which establishes communication between the rag-filled main chamber 3 and a supplementary rag-filled chamber 11. The top of chamber 11 is provided by the aforesaid shelf 9, the latter extending outwardly into relatively close proximity to a baffle plate 12, here shown as supported by walls 13, 13 that constitute the sides of chamber 11. The bottom 14 of chamber 11 preferably slopes sharply upwardly from the opening 10, and along the upper edge of said bottom is provided a dam or obstruction 15 which is appreciably above the level of the lower edge of baffle plate 12 and is spaced substantially outward from said baffle plate 12, thus to leave the chamber 11 open between plate 12 and dam 15 for the outward flow, over said dam, of the "gangue" or waste matter in the pulp, as hereinafter described.

20 The base 1 supports another shell 16 which provides, below the plate or rack 6, another chamber 17, the bottom of said chamber being constituted by a removable screen 18. Any suitable means are provided to permit removal of a screen 18 and the substitution in its place of 25 a similar screen of different mesh; as here shown, the screen is removably clamped between flanges 19 and 20 provided, respectively, by the shell 16 and by another shell 21 below the screen, said last-named shell inclosing a chamber 22 to 30 which the pulp has access by way of the apertures in screen 18. Preferably, for a fine-ground pulp, a screen 18 of fine mesh is employed, while if the pulp is coarse-ground, a screen of larger mesh is used; in any case, the mesh of such 35 screen must be large enough for the solid particles of the pulp to pass through it, but in no case must the mesh allow the passage through the screen of the "rags" 23, 23 supported thereon within the chamber 17—these "rags", as shown. 40 being preferably smaller in size than the "rags" 45 7 which are contained in the chambers 3 and 11.

Within the chamber 17, between the "rags" 23 and the plate 6, is arranged a preferably annular nozzle pipe 24, having a plurality of jet openings 50 for the impingement, as hereinafter described, of streams or jets of water and steam into the pulp and against the mass of "rags" 7 above and against the layers of "rags" 23 below. Within the chamber 22 is a baffle or guard 25, arranged over the open mouth of a nozzle pipe 26, to prevent direct impingement of the water and steam discharge from said nozzle against the screen 18. The outlet from chamber 22 is indicated at 27, and is provided with a suitable 60 valve 28, the position of which is adjusted by the setting of an operating handle 29, so as to govern the rate of discharge of the concentrate from chamber 22 into an open offtake passage 30, the latter being preferably equipped with a 65 suitable baffle 30'. In said offtake passage 30, the concentrated pulp flows by gravity through an opening 31 into a pumping chamber 32—the opening 31 being controlled by a suitable check valve 33, preferably of the "flapper" type, which 70 is adapted to permit the passage of the concentrate through the opening 31 in one direction only, viz., from the offtake into the chamber; the valve 33 automatically closes whenever the 75 pressure in the chamber 32 tends to cause any flow of the concentrate through opening 31 in

the reverse direction. The pumping action in each chamber 32 is preferably effected by the admission to said chamber of steam, air, or other gas, under pressure, as by means of a pipe 34 which lets into each chamber 32 near the top 5 thereof—the two pipes 34 branching, as herein shown, from a pressure fluid supply pipe 35 in which is preferably arranged a mechanically operated valve 36. The valve 36 is adapted, in the operation of the system, to be alternately opened and closed, at a regulable rate to produce a more or less rapid pulsation in the admission of fluid pressure to the chambers 32—this pressure in each chamber being communicated to the liquid-carried concentrate in the 15 lower part of the chamber, to force said material upwardly through a pipe 37 which communicates with the entrance tube 4 of the next succeeding trap of the series.

The main 38 which furnishes pressure fluid 20 for pump supply pipe 35 may also furnish pressure fluid to another supply pipe 39 having therein a suitable mechanically operated valve 40 which, like the valve 36, is alternately opened and closed in order to give the steam or other 25 gas, along with the water or other liquid which is admitted to each trap, a pulsating action that agitates the "rags" 7 and 23 and contributes very materially to the separation of the "gangue" from the "values", as hereinafter described. Beyond the valve 40, the pressure supply pipe 39 has a branch 41, equipped with a hand throttle valve 42; from this branch 41, the steam, air, or other gas, under pressure is supplied by a connection 43 to the entrance duct 4 of each 35 trap, the impulses through each connection 43 being in a downward direction into the pulp as it enters each trap, and said impulses serving to counteract and cushion any tendency of the entering pulp to be blown back through duct 4 40 by the upwardly directed fluid jets from the associated nozzle 24.

Provision is made for obtaining pulsating discharges of fluid, preferably water and steam, into each trap, not only through the annular 45 nozzle 24 and the nozzle pipe 26, but also through a plurality of jet openings 44 provided in the bottom 14 of chamber 11, these jet openings being supplied from a chamber 45. As shown in the drawing for illustrative purposes, these pulsating fluid discharges into each trap may be obtained by a branch connection 46 connecting the steam supply pipe 39 with a main 47 through which water or other liquid circulates in the direction of the arrows; from main 47, there is 50 a branch connection 48 to each trap, the latter providing a valved feeder 49 to the chamber 45 and a valved extension 50 that feeds both the nozzle pipe 26 and the annular nozzle 24. The steam pulsations of supply pipe 39 are thus impressed on the liquid that is discharged into each trap by the nozzle pipe 26 and jet openings 24 and 44, the steam from branch 46 being to a certain extent mixed and mingled with the liquid discharged through these openings; this pulsating effect is preferably made even more pronounced and the mixture of liquid and gas made even more intimate by another steam branch 51 from supply 39, said branch having a connection 52 to each trap that joins the feeder 50 in the 55 vicinity of the latter's connection to the annular nozzle 24. The operation of the apparatus as thus far described is substantially as follows:

The supply of pulp which flows by way of a suitable conduit 53 to the entrance tube 4 of the 75

first trap is forced downward in said tube by the pulsating discharges of steam from pipe 43, and is met at the lower end of tube 4 with a regulated upward pulsating discharge of liquid and steam from annular nozzle 24, these jets impinging on the coarse "rags" 1, 1 that substantially fill the chamber 3. At each pulsation, the "rags" 1 shift slightly upward and then settle downward by gravity, this agitation of the "rags" 1 being accompanied by the gradual working-up through said "rags" of the lighter particles carried in suspension by the pulp, which lighter particles are naturally more susceptible to the lifting action of the upwardly directed jets from nozzle 24 than are the heavier particles or "values" contained in said pulp—although in this initial separation of the "lights" from the "heavies", the ascending "lights" will be accompanied by some of the "heavies", particularly the somewhat more finely ground "heavies". Also the descending "heavies" will be accompanied by some of the "lights", the descending particles in pulp form sifting down through the bottom layer of "rags" 1, 1 on the rack 6 and passing through the perforations of said rack into the separating chamber 17 which, it will be understood, fills up with a liquid pulp in which, due to the initial separating action above described, the portion of "heavies" is greater than in the entering pulp, because of the considerable proportion of "lights" driven upwardly into the "rags" 1, 1 of chamber 3.

These particles, both "lights" and "heavies", that ascend in pulp form in chamber 3 will gradually flow out of said chamber through opening 8 onto shelf 9, and will accumulate on said shelf in the form of a progressively rising dam, as indicated at 54, which acts to retard any tendency of this thin pulp or slime to flow too rapidly out through the opening 8. Said pulp, discharging over the dam 54, and containing "lights" and the finer "heavies" in suspension, flows by gravity into supplementary separating chamber 11, the latter, as aforesaid, containing "rags" 1, 1 which are agitated by the pulsating jets of fluid, preferably water and steam, discharged through the openings 44. Consequently, in chamber 11 occurs a separation of "lights" from "heavies" similar to that occurring in chamber 3—the "heavies" working down through the "rags" of chamber 11 to reenter the chamber 3 through opening 10, while the "lights", by the elevating action of the jets of water and steam from openings 44, are caused to work up through the "rags" in chamber 11 toward the open portion of said chamber beyond the baffle 12, whence they are discharged continuously in a thin pulp or slime over the dam 15 and into a suitable offtake trough 55 for the disposal of this waste material. Thus, in chamber 11 occurs an almost complete recovery of "values" which would otherwise be carried off and discarded with the "gangue" or worthless portion of the pulp—these "values" being returned, as above described, through opening 10 for the enrichment of the somewhat refined or concentrated pulp that, as above described, is constantly passing down through rack 6 into chamber 17.

In the chambers 11 and 22, separated by screen 18, the pulp undergoes a further concentration, by the pulsating steam and water discharges of nozzle pipe 26 and the downwardly directed jet openings of annular nozzle 24—these combined discharges producing an agitation or intermittent working up and down of the finer "rags" 23 on screen 18, that allows the "heavies"

to sift down through said screen while freeing and forcing upwardly a considerable portion of the "lights" until some of the latter at least come under the influence of the upwardly directed jets of annular nozzle 24, and are thus forced back into the mass of "rags" 1 of chamber 3, for ultimate discharge with the worthless slime that passes out over the dam 15. Thus the pulp that reaches the bottom of chamber 22 is considerably richer and more concentrated in "heavies" than the pulp which enters the first trap.

The concentrated pulp has its outflow from chamber 22 by way of passage 27, and it will be obvious that the position of adjustment of the valve 28 in passage 27 governs not only the rate of flow of the concentrated pulp into offtake 30, but also, indirectly, the rate of discharge of the slimes which carry off the "gangue" into trough 55. In other words, the valve 28 is so adjusted by the operator as to maintain the proper balance between the rate of inflow of the entering pulp, and the rate of outflow of the concentrated pulp, for an efficient and economical partial separation of the "lights" from the "heavies" in any given pulp; these conditions vary widely with different kinds and grades of pulp and with different varieties of ores and metal-bearing sands, and provision is accordingly made for inspection and testing of the pulp at appropriate points, to determine its degree of concentration, and in accordance with such determination to change, if necessary, the setting of the valve 28, and to increase or decrease, as required, the amount of steam and water admitted to the trap, by suitable opening or closing movements of the valves that are provided in the feed lines 49 and 50. To permit of such inspection and testing of the concentrate, each pump chamber 32 near its bottom may be equipped with a draw-off cock 56; in addition, each pipe or duct 37 through which the concentrated pulp is forced, by pressure in said pump chamber to the next trap of the series, may provide, as shown, a fitting or enlargement 57 which is open, not only to permit inspection of the passing material, but also to maintain said material substantially at atmospheric pressure, as it flows into the next trap.

The pulp material allowed to discharge into offtake 30 of the first trap flows through opening 31 into pump chamber 32; this pulp, which contains considerably less of the "gangue" than the original entering pulp, may require the addition of some water to restore the free-flowing character of the pulp, in its passage through pipe 37 to the next trap of the series; if additional water is needed, the same may be readily supplied by admitting it directly to the offtake 30 which is open to the atmosphere. The next trap of the series, as shown, is in all respects the duplicate in construction of the first trap, but is preferably made considerably smaller in size, as it is not required to handle in a given time as great a volume of the richer pulp as the volume of original pulp introduced in the same time to the first trap. In other words, assuming the originally entering pulp and the enriched pulp to be of substantially the same consistency (the same proportion of solids to liquids), it is clear that the very considerable quantity of "lights" that pass off, as above described, with the slimes from the top of the first trap secures an appreciable reduction in the volume of material that passes to the second trap—and so on for subsequent traps of the series which in number

be as many or as few as required. The progressive separating action above described by which the "lights" are all the time being thrown off, causing the pulp to become relatively richer and richer in "heavies", takes place in each of the succeeding traps of the series in exactly the same manner as above described for the first trap. Finally, in the smallest or last trap of the series (here shown as the third trap for convenience of illustration), the concentrate attains such a preponderance of "heavies" as to make further concentration impracticable; in this last trap, the construction may be slightly different in providing below the screen 18 a second screen 58, the latter being held between a casing member 21' and an additional casing member 59, inclosing a chamber 60. The material which works down through the layer of "rags" 61 on screen 58 is an enriched pulp in which the solid matter is practically all "heavies", the last of the "gangue" or worthless "lights" having been discharged into the trough 55 of the final trap. This concentrated pulp is allowed to accumulate in chamber 60 or may be drawn off as a substantially constant discharge through outlet 62, and screened to separate the solids from the liquid—the solids being almost wholly composed of the heavier mineral particles or "values" in a form suitable for reduction by smelting or otherwise.

There is never any need, in the operation of my improved process and apparatus, to shut down or to discontinue temporarily the feeding in of the material in order to permit accumulated "values" to be collected. As distinguished from most ordinary concentrating operations, where considerable percentages of the "values" or heavies do not participate in the flow of the mass of pulp through the apparatus, but are left behind for collection on subsequent periodic shut-downs in the delivery of the material, in my concentrating operation, the "values" are carried along progressively through the entire apparatus, the latter functioning to obtain in a series of stages a progressive transformation both quantitatively and qualitatively of the stream of pulp that flows therethrough. Said pulp stream, by virtue of the slimes discarded therefrom in the first trap of the series, is rendered materially smaller in volume and relatively richer in "values"; thereupon by the subjection of this intermediate product as fast as formed to the second trap of the series, is obtained a stream of pulp residue still smaller in volume and more concentrated in "values". And so on, as successive traps are encountered by these gradually diminishing and increasingly concentrated streams of the pulp which, in each case, carry along practically all of the originally-present heavier ingredients or "values"—until finally, from the last and smallest trap of the series is obtained a pulp delivery at a volumetric rate which is only a very small fraction of the volumetric rate of feed of the original pulp; however, in this final discharge from chamber 60 of the last trap, the heavies or "values" are so predominant as to make further concentration unnecessary. Such small discharge from the bottom of the last trap is the sole product of my process; such discharge retains practically all of the "values" and is free of practically all of the "gangue" that entered with the original pulp. In the operation of my process, this final end product discharging from the bottom

of the last trap is always being continuously and progressively produced, so that the process in its entirety is truly continuous throughout—there being no need for any interruptions in the delivery of the original pulp stream to the system, nor for any interruptions in the passage of the gradually-diminishing pulp stream therethrough.

Although the pulp liquid may be used over and over again in the system, there is no tendency of the same to sour or to become polluted, since there is a continuous addition thereto of live steam which has a beneficial purifying action in destroying any fungus or bacteria that enters with the ore, sand, or other material being treated. This continuous introduction of steam to the pulp stream substantially replenishes all water or pulp liquid that is lost by the periodic removal of the sediments from the slimes that flow off through the troughs 55, 55 by the discharge of the final pulp concentrate from chamber 60—this enabling the apparatus to be operated economically even in regions where water is scarce and expensive.

I claim:

1. In ore concentrating apparatus of the class described, for the separation of "lights" from "heavies" in a free-flowing pulp, a pulp-receiving chamber having a screen at its bottom, a mass of "rags" in said chamber supported on said screen, the latter's perforations permitting passage therethrough of all the solid matter of said pulp, means for producing intermittent upward surges of fluid through said chamber, to agitate the "rags" therein and to discharge upwardly through said "rags" some of the lighter particles of the pulp, a second chamber communicating with the top of said first chamber and receiving therefrom said upwardly discharged material, a mass of "rags" in said second chamber, means for producing in said second chamber intermittent surges of fluid for the alternate elevations and settling of the "rags" therein, thereby to float off the lighter pulp particles in said second chamber and to cause settling through said "rags" of the heavier pulp particles, and a substantially horizontal shelf in the path of pulp flow from the first chamber to the second chamber, said shelf providing for the support, in dam formation, of lighter pulp particles deposited by said pulp flow.

2. In ore concentrating apparatus of the class described, for the separation of "lights" from "heavies" in a free-flowing pulp, a pulp-receiving chamber containing a mass of "rags", the bottom of said chamber having perforations therein of such size as to permit passage therethrough of all the solid ingredients of said pulp, but to prevent passage therethrough of any of said "rags", means for producing intermittent upward surges of fluid against said "rags" coincident with the downward gravitational passage therethrough of the pulp, thereby through alternate elevations and settling of said "rags" to float off the lighter pulp particles and to cause descent through said "rags" of heavier pulp particles, an outlet from the upper part of said chamber above said "rag" mass, for said lighter floated-off particles, and a substantially horizontal shelf, associated with said outlet, and whereon said floated-off lighter particles find support to form a dam.

HARRY H. BURTON.
